Primary Examiner — T. Chase Nelson*Assistant Examiner* — Jonathan J. Han(74) *Attorney, Agent, or Firm* — Banner & Witcoff, Ltd.(57) **CLAIM**

The ornamental design for a shoe, as shown and described.

DESCRIPTION

FIG. 1 is a front perspective view of a shoe showing my new design;

FIG. 2 is a side view thereof;

FIG. 3 is an opposite side view thereof;

FIG. 4 is a rear view thereof; and,

FIG. 5 is an enlarged partial view of FIG. 2.

The solid lines that are not immediately adjacent to the shaded area are claimed. The broken lines showing the remainder of the shoe represent unclaimed subject matter and form no part of the claimed design.
